R. M. Dill.
Shuttle Check.

N° 13,217.

Patented Jul. 10, 1855.

UNITED STATES PATENT OFFICE.

RUFUS M. DILL, OF HOLYOKE, MASSACHUSETTS.

LOOM.

Specification of Letters Patent No. 13,217, dated July 10, 1855.

To all whom it may concern:

Be it known that I, RUFUS M. DILL, of 5
Holyoke, in the county of Hampden and
State of Massachusetts, have invented a new
and useful Improvement in Shuttle-Stops
for Looms with Changing Shuttle-Boxes;
and I hereby declare that the following is a
full and exact description of the construc-
tion and operation thereof, reference being
had to the accompanying drawings, making
10 a part of this specification, in which—

Figure 1, is an isometrical view of a part
of the left hand end of a loom, with the
shuttle stop in connection with a double
15 shuttle box and its appendages. Fig. 2 is
an end elevation of the shuttle-stop de-
tached. Fig. 3 is a front elevation of a part
of the same.

The same letters indicate like parts in all
20 the figures.

A, Fig. 1 is the shuttle-stop attached
loosely to the arm B, of the lay, by the
screws a, a, passing through the slots b, b,
(one of which is shown at Fig. 1 and the
25 other at Fig. 3) to allow it to slide or trav-
erse on said screws, and in contact with,
and parallel to the arm B of the lay, by
the action of the stud c, traveling in the di-
agonal groove d, (attached to the top of the
30 frame G) as the lay beats back and forth,
the top of the groove d being the arc of a
circle, described from the center of the
rockers H. The vertical arm of the stop A,
is formed with two projections, D D, pro-
35 jecting inward toward, and into, the shuttle
box F the same distance as the picker C, and
at such distance apart that when the bottom
shuttle is in the position to be acted upon by
the picker C, the top shuttle will be hori-
40 zontally in line with the top projection, (as
shown in the drawing Fig. 1) and when the
top shuttle is in the position to be acted
upon by the picker, the bottom shuttle will
be in line with the bottom projection. The
45 face of the projections stands forward over

that part of the stop that comes in contact
with the picker, the width of the picker,
bringing the face of the projections verti-
cally in line with the face of the picker;
(see Fig. 3) thus, at each beat of the lay 50
making sure that both of the shuttles E, E,
are forward in the shuttle boxes to the ex-
tent of the forward traverse of the stop A,
and the points of the shuttles one directly
over the other, rendering it impossible to 55
get either shuttle far enough into the boxes
to catch against the picker when the box
changes; whether they be thrown into the
box by the action of the opposite picker, or
placed in by hand after threading, or chang- 60
ing the shuttles. The picker C, is driven
outward against the stop by the action of
springs attached to the picker staff N, in the
usual manner.

I would here say that I do not limit my-
self to any particular number of boxes in
the series, as the stop can be applied to any
number and have the effect to keep all the
shuttles forward in their places by making
one less projections than boxes, both above, 65
and below the picker.

I am aware that a slotted lever, operated
by a pin in the lay, has been used in looms
with movable shuttle boxes to hold the
picker forward and thereby stop the shuttle, 70
and therefore I do not claim such; but

What I do claim and desire to secure by
Letters Patent, is—

A sliding bar, attached to the lay, having
projections adapted to each shuttle box of a 80
series at its outer end, and actuated from the
inner end by a groove attached to the frame
of the loom; substantially in the manner,
and for the purpose described.

Holyoke May 31, 1855.

RUFUS M. DILL.

Witnesses:

STEPHEN HOLMAN,
W.M. GROVER.
